Primary Examiner — Cynthia M. Chin(74) *Attorney, Agent, or Firm* — Pillsbury Winthrop Shaw Pittman LLP(57) **CLAIM**

The ornamental design for a robotic toy, as shown and described.

DESCRIPTION

FIG. 1 is a perspective view of a robotic toy embodying an aspect of the design;

FIG. 2 is a front view of the toy of FIG. 1;

FIG. 3 is a back view of the toy of FIG. 1;

FIG. 4 is a top view of the toy of FIG. 1;

FIG. 5 is a bottom view of the toy of FIG. 1;

FIG. 6 is a left view of the toy of FIG. 1;

FIG. 7 is a right view of the toy of FIG. 1;

FIG. 8 is a cross-sectional view taken along line 8-8 in FIG. 2;

FIG. 9 is a left side, perspective view of the cross-section of FIG. 8;

FIG. 10 is a right side, perspective view of the cross-section;

FIG. 11 is a cross-sectional view taken along line 11-11 in FIG. 2;

FIG. 12 is a front perspective view of the cross-section of FIG. 11; and,

FIG. 13 is a perspective view of the cross-section.

In the drawings, the broken lines depicting portions of the toy form no part of the claimed design; all other broken lines depict unclaimed environmental subject matter and form no part of the claimed design.

1 Claim, 13 Drawing Sheets(56)
